BARN TOY

Robert I. Genin, Scarsdale, N.Y., assignor to Questor Corporation, Toledo, Ohio

Filed Feb. 22, 1971, Ser. No. 117,873

Term of patent 14 years

Int. Cl. D21—01

U.S. Cl. D34—15 LL

FIG. 1

FIG. 2

FIG. 3

FIG. 4

FIG. 6

FIG. 5

FIG. 1 is a top plan view of a barn toy showing my new design;

FIG. 2 is a front elevational view;

FIG. 3 is a rear elevation view;

FIG. 4 is an end view taken from the left of FIG. 2;

FIG. 5 is an end view taken from the right of FIG. 2; and

FIG. 6 is a top perspective view thereof.

The cow figure is affixed to the base of the barn.

I claim:

The ornamental design for a barn toy, as shown and described.
